Des. 189,734
Patented Feb. 7, 1961

189,734

FONT OF THREE-DIMENSIONAL DISPLAY LETTERS

Peter Dom, New York, N.Y., assignor to Frank P. Mitten, Redlands, Calif.

Filed Dec. 13, 1956, Ser. No. 44,171

Term of patent 14 years

(Cl. D64—12)

The figure of the drawing is a perspective view of a font of three-dimensional display letters illustrating my new design as it appears against a dark background.

I claim:

The ornamental design for a font of three-dimensional display letters, substantially as shown and described.
